UNITED STATES PATENT OFFICE.

WILLIAM A. WARMAN, OF NEW YORK, N. Y.

AIR COMPRESSOR OR MOTOR.

1,109,805.

Specification of Letters Patent.

Patented Sept. 8, 1914.

Application filed October 24, 1913. Serial No. 796,999.

To all whom it may concern:

Be it known that I, WILLIAM A. WARMAN, a citizen of the United States, and a resident of New York, borough of Manhattan, in the county of New York and State of New York, have made and invented certain new and useful Improvements in Air Compressors or Motors, of which the following is a specification.

10 My invention relates to air or gas compressors, air operated motors, fluid operated engines, etc., that is, to devices capable of use either as a pump or compressor, or as an engine, and particularly to that type of compressor in which a cylinder member having a plurality of radiating cylinders rotating about a stationary valve member is employed.

Compressors of the type above referred to 20 employ a reciprocating piston in each separate cylinder, and the object of my invention is to provide, in such a compressor or engine, improved mechanism for imparting reciprocating motion to the pistons as the cylinder member is rotated, or for converting the reciprocating motion of the pistons into rotary motion of the cylinder member and a driving shaft.

With the above and other objects in view, 30 my invention consists in the improved pump or motor construction illustrated in the accompanying drawings and hereinafter described and claimed, and in such variations and modifications thereof as will be obvious to those skilled in the art to which my invention relates.

In the drawings wherein the preferred embodiment of my invention is illustrated: Figure 1 is a view showing a section of my improved motor or pump upon a vertical transverse plane indicated by the broken line 1—1, Fig. 2; Fig. 2 is a view showing a section upon a horizontal plane indicated by the broken line 2—2, Fig. 1; Fig. 3 is a view showing a section upon a vertical transverse plane indicated by the broken line 3—3, Fig. 2; Fig. 4 is a fragmentary view showing a section upon a vertical transverse plane indicated by the line 4—4, Fig. 2; Fig. 5 is a similar view showing a section upon a vertical longitudinal plane indicated by the line 5—5, Fig. 4, looking toward the left; Fig. 6 is a view similar to Fig. 3, but showing the parts in another position; Fig. 7 is a view showing the valve member of my device as seen from a position

to the left of Fig. 5; Fig. 8 is a view showing the valve member in side elevation; Fig. 9 is a view showing said member in plan; Fig. 10 is a view showing one of four eccentric disks employed in the form of my invention illustrated; Fig. 11 is a view showing an eccentric strap and yoke forming a part of my device assembled and in end elevation, referred to the device as a whole; and, Fig. 12 is a view showing said elements in side elevation.

Referring to the drawings, the reference numeral 15 designates two similar parts of an external casing within which the operating parts of my improved pump and motor are contained, 16 designates a stationary valve member supported from said casing, and 17 designates a bearing also supported from the casing and through which the shaft 70 18 extends, which shaft, as will be understood, serves as either a driven or a driving shaft, with reference to external devices, according to whether my device is used as a pump or as a motor. The valve member is 75 provided with suitable inlet and discharge passages 19, 20, assuming the device to be used as a compressor. Located within the casing aforesaid and rotatable about the stationary valve member is a cylinder member 21 having a plurality of radially extending cylinders, four such cylinders 22, 23, 24, 25 arranged at right angles to one another being employed in the embodiment of my invention illustrated. Within each cylinder is 80 located a reciprocating piston to which the reference numerals 26, 27, 28 and 29 are applied. The cylinders and pistons are 85 preferably made comparatively long with reference to the stroke, so as to avoid the 90 necessity of separate means for guiding the pistons in their movements, the cylinder walls forming the necessary guiding means.

The mechanism whereby reciprocating motion is communicated to the pistons as the 95 cylinder member 21 rotates comprises two stationary eccentric disks 30, 31 shown as secured to the valve member 16 by means of screws 32, the relative position of the disks being such that the pistons 26, 28 in two oppositely located cylinders, see Fig. 3, will be moved simultaneously in opposite directions as the cylinder member rotates; and two eccentric straps 33, 34 surrounding said disks and which straps are operatively connected 105 with the pistons above referred to. The other pistons 27, 29 are operated by means of

two operating members 35, 36 shown as in the form of yokes having a central opening large enough to clear the eccentric disks and straps when the device is in operation, one 5 end of the yoke 35 being pivotally connected with the strap 33 at 37, while the yoke 36 is connected in a like way with the strap 34 at 38. The outer ends of these yokes are operatively connected with the pistons 27, 29, 10 see Fig. 3, from which construction it will be obvious that said last-mentioned pistons will also be moved simultaneously in opposite direction as the cylinder member 21 rotates.

15 I prefer to duplicate the operating mechanism above referred to upon the side of the cylinder member adjacent the bearing 17 in order that the force acting upon the pistons may not tend to tip them and cause unequal 20 wear, or binding in the cylinders. Thus the reference numerals 39, 40, see Fig. 2, designate eccentric disks similar to the disks 30, 31 and similarly arranged, which disks are secured to the bearing 17 by means of screws 25 shown in dotted lines.

The numerals 41, 42 designate yokes similar to the yokes 35, 36, and the inner ends of which are pivotally connected with the eccentric straps 43, 44 which surround the 30 disks 39, 40. The outer ends of the yokes 35 and 41 are secured to a cross bar 45 carried by the piston 27, and, as the said yokes move simultaneously in the same direction, it will be seen that the ends of the bar are 35 subjected to equal pulls, and that force is transmitted to the piston along its center line. In like manner the free ends of the yokes 36, 42 are connected with the piston 29 through a cross-bar 46. It will be understood 40 that the eccentric straps 43, 44 are connected with the pistons 26, 28 in a similar way, and act in connection with the straps 33, 34 to operate said pistons. Although such connections are not actually shown, the 45 upper and lower free ends of the straps 43, 44 lie back of and are hidden by the straps 33, 34, Fig. 1, as will be understood from Fig. 6 in which the greater part of the duplicated operating mechanism located adjacent the bearing 17 appears in dotted lines, as it lies beyond the rotating cylinder member appearing in that figure. The main shaft 18 is operatively connected with the 50 rotating cylinder member 21 in any way as by means of a flange 47 secured to said member by suitable screws. Such being the construction of my improved motor or pump, it will be seen that as the cylinder member rotates, the pistons in each pair of oppositely located cylinders will move simultaneously toward and from one another. Thus, referring to Fig. 3, and assuming the device to be used as an air compressor, and remembering that the corresponding position of 55 the piston operating mechanism is as is illus-

trated in Fig. 1, rotation of the cylinder member in the direction indicated by the arrow will be accompanied by a simultaneous inward movement of all the pistons, the pistons 26, 28 having just begun their 70 inward movement while the pistons 27, 29 have moved through about one-half of their inward movement. This inward movement of the pistons will be accompanied by a discharge of air under pressure from all of the 75 cylinders, the discharge from the cylinders 22, 23 taking place through ports 48 in the cylinder heads and through a recess 49 provided in the valve member and a passage 50 into the discharge passage 20 of the valve 80 member. At the same time air will be discharged from the cylinders 24, 25, see Fig. 4, through ports 51 in the cylinder heads, and through a recess 52 provided in the valve member and a passage 53 into the discharge 85 20 of the valve member. The discharge recesses 49 and 52 are offset from one another, as shown in Figs. 2 and 9, and the views shown in Figs. 3 and 4 are upon different planes, as hereinbefore explained. 90

After the cylinder member has been rotated through 180° the various parts will occupy the positions shown in full and in dotted lines in Fig. 6, and all the pistons will move outward as the cylinder member 95 continues its rotation. Upon further rotation in the direction indicated by the arrow, the ports 51 in the cylinders 24, 25, see Fig. 4, will communicate with a recess 54 in the valve member, which recess is in communication with the supply or inlet passage 19 through a passage 55, and air will flow into these cylinders. At the same time the ports 48 in the cylinders 22, 23, see Fig. 6, will communicate with a recess 56 in the valve 100 member, which recess is likewise in communication with the inlet passage 19 through a passage 57, and air will also flow into these cylinders. The supply recesses 54, 56 are offset in the same manner as the discharge 105 recesses 49, 52, see Fig. 9, the supply and discharge recesses being located opposite one another, as shown in Figs. 2, 8 and 9, and separated by walls 58 as will be understood. 110

Having thus described and explained my 115 invention, I claim and desire to secure by Letters Patent:

1. In a device of the class described, a stationary valve member; a cylinder member rotatable about said valve member and having a plurality of radiating cylinders; a reciprocating piston in each of said cylinders; a stationary eccentric disk; an eccentric strap surrounding said disk and operatively connected with one of said pistons; an operating member one end of which is pivotally connected with said strap and the other end with another of said pistons; and a driving shaft operatively connected with said cylinder member. 120 125 130

2. In a device of the class described, a suitable casing; a stationary valve member supported by said casing; a cylinder member within said casing and rotatable about said valve member and having a plurality of radiating cylinders; a reciprocating piston in each of said cylinders; two similarly arranged stationary eccentric disks located one upon each side of said cylinder member; two eccentric straps one surrounding each of said disks and which straps are operatively connected with one of the pistons aforesaid; two operating members, one end of each of which is pivotally connected with one of said straps, and the other ends of which are operatively connected with another of said pistons; a bearing carried by said casing; and a driving shaft extending through said bearing and operatively connected with said cylinder member. 5
3. In a device of the class described, a stationary valve member; a cylinder member rotatable about said valve member and having a plurality of radiating cylinders; a reciprocating piston in each of said cylinders; a stationary eccentric disk supported by said valve member; an eccentric strap surrounding said disk and operatively connected with one of said pistons; a yoke surrounding said disk and strap, one end thereof being pivotally connected with said strap and the other end operatively connected with another of said pistons; and a driving shaft operatively connected with said cylinder member. 10
4. In a device of the class described, a stationary valve member; a cylinder member rotatable about said valve member and having four radiating cylinders arranged at right angles to one another; a reciprocating piston in each of said cylinders; two stationary eccentric disks carried by said valve member and arranged opposite one another, so as to move their straps simultaneously in opposite directions; two eccentric straps, one surrounding each of said disks and which straps are operatively connected one with each of two oppositely located pistons; two operating members, one end of each of which is pivotally connected with one of said straps, and the other ends of which are operatively connected with the two remaining pistons; and a driving shaft operatively connected with said cylinder member. 15
5. In a device of the class described, a suitable casing; a stationary valve member supported by said casing; a cylinder member supported by and rotatable about said valve member and having four radiating cylinders arranged at right angles to one another; a reciprocating piston in each of said cylinders; two stationary eccentric disks carried by said valve member and arranged opposite one another, so as to move their straps simultaneously in opposite directions; two eccentric straps, one surrounding each of said disks and which straps are operatively connected one with each of two oppositely located pistons; two yokes, one end of each of which is pivotally connected with one of said straps, and the other ends of which are operatively connected with the two remaining pistons; and a driven shaft operatively connected with said cylinder member. 20

Signed at New York, borough of Manhattan, in the county of New York and State of New York, this 21st day of October, A. D. 1913.
